Edwards, Sager & Bowes

UNITED STATES PATENT OFFICE.

ROBERT V. BINGAY, OF PITTSBURGH, PENNSYLVANIA, ASSIGNOR TO PITTSBURGH TRANSFORMER COMPANY, A CORPORATION OF PENNSYLVANIA.

PROTECTION OF ALTERNATING-CURRENT-DISTRIBUTING CIRCUITS.

Application filed October 17, 1919. Serial No. 331,322.

To all whom it may concern:

Be it known that I, ROBERT V. BINGAY, a citizen of the United States, residing at Pittsburgh, in the county of Allegheny and State of Pennsylvania, have invented certain new and useful Improvements in Protection of Alternating-Current-Distributing Circuits, of which the following is a specification.

10 My invention relates to the protection of alternating current circuits and apparatus, and particularly to the protection of the low tension or distributing circuits and to the apparatus supplied thereby where the source 15 is of high tension and where the reduction of the high voltage to the low voltage of distribution is by means of transformers or other apparatus.

It sometimes happens that the insulation 20 between the high tension circuits or high tension coils of the transforming apparatus and the low tension coils or low tension-circuits, breaks down so that some point of the low tension side is electrically connected to some 25 point of the high tension side. This may occur from various causes such as a break-down of the insulation directly between the high tension and low tension coils of the step-down transformer, or the connection 30 between the high and low tension coils may occur indirectly between the coils through the iron core or iron casing of the transformer, or between the leads directly or indirectly. In such an event, the high potential 35 of the high tension system is superimposed upon the low tension portion of the system. With such a condition the low tension portion of the system is correspondingly subjected to the potential of the point 40 of break-down in the high tension side of the system, and this may be extremely high and very much exceed the potential intended to be imposed upon the secondary portion or portions of the system. This condition 45 imposes upon the secondary circuit such an abnormally high potential that it becomes a source of danger to users and to the various apparatus connected to the distribution system. It also becomes a menace to other 50 property and greatly increases the fire hazard. With the two-wire distributing circuits, there is no normal neutral point available for grounding and attempts to secure protection by grounding one side or the 55 other of the two-wire distributing means have proven unsatisfactory. In accordance with my invention, however, I introduce means connected between the two-wire low tension distributing mains for the purpose of providing a neutral point, which point 60 is in turn connected to the ground. By this means, the system is not in any way unbalanced and by reason of this ground connection to a created neutral point, the potential to which any point in the secondary 65 distributing system may be raised above or below that of the earth, is restricted to a fixed amount, which would be less than might occur without the ground connection. Furthermore, the low tension circuits and the 70 apparatus connected therewith are relieved from high electro-static charges by reason of my improved form and location of ground connection, which relieves the circuits and apparatus from high potential strains, which 75 might otherwise occur, and which would subject such circuits and apparatus to the liability of break-down of their insulation. Again the provision of my improved ground connection will, in the case of abnormal 80 connection between the high tension and low tension portions of the system as above referred to, result in some cases in the immediate opening of the circuit breakers and fuses or other protective apparatus caused by the 85 sudden and abnormal flow of current, so as to entirely disconnect the secondary distributing circuit from the source and so prevent danger to persons and to property 90 which otherwise might occur.

95 My invention will be understood by referring to the accompanying drawing which is a diagram illustrating my invention.

A source of alternating current is indicated at 1 which may be of very high tension so as to supply the high tension mains directly, or the source may be of comparatively low tension and a step-up transformer 2 may be utilized for supplying the high tension constant potential transmission 100 mains 3. Step-down transformers are indicated at 4 and 5 located at desired points for supplying the low tension constant potential two-wire distributing circuits 6, 7. Reactance coils are indicated at 8, 9 each 105 having an iron core 10, 11. Leads 12, 13 extend from terminals or taps from the coils 8, 9 connecting these coils in circuit across the two-wire distributing mains. At the middle point of each coil an electrical connection is 110

made to ground, which ground connection is represented at G. The reactance coils and the core will be suitably proportioned so as to absorb but a small amount of energy from the circuits and in order to adapt or adjust the reactance coils to circuits of different voltages I have shown the reactance coils as being provided with taps near their ends to which the leads from the distributing circuits may be connected as required by the particular conditions.

It will be apparent that the reactance coils provide a neutral point at a position in the coil midway between the points of the coils which are connected respectively to the two wires of the distributing circuits and that by making a ground connection to this neutral point as indicated in the drawing, the secondary circuits are suitably grounded in a balanced manner affording the protection above referred to with the attendant advantages. For instance in case of a high tension ground as G' and a failure of the insulation between the high tension circuit and low tension circuit 7 as at S, were it not for the shunt provided by the reactance coil 9 and the ground at G, the full high tension voltage would be impressed between the wires of the low tension circuit and the ground, as G''. Such a voltage would be destructive in the low tension system burning out apparatus and instruments that happened to be grounded and endangering the lives of persons coming between the wires and grounded parts. In the system shown excessive current through the coil 9 due to connection with the high tension line may act to disconnect the secondary as by operating the usual protective switches in the circuit and thus afford further protection.

My invention is susceptible of embodiment in various forms without departing from

the scope thereof, and is also capable of being applied at any desired point or points in the distributing system.

Having thus described my invention, what I declare as new and desire to secure by Letters Patent of the United States is:—

1. In an alternating current system the combination with a high tension source, of a low tension two-wire distributing circuit, means for transforming energy of the high tension source to the low tension of the distributing circuit, a reactance coil connected across the wires of said distributing circuit, and a ground connection from approximately the neutral point of said reactance coil protecting said low tension circuit against the voltage of the high tension circuit.

2. In an alternating current system the combination with a high tension source, of a low tension two-wire distributing circuit, means for transforming energy of the high tension source to the low tension of the distributing circuit, a reactance coil connected across the two-wires of said distributing circuit and having a plurality of taps, and a ground connection to a point at a potential approximately midway between the potentials of the two wires of said distributing circuit protecting said low tension circuit against the voltage of the high tension circuit.

3. In an alternating current system, the combination with a transformer having high and low tension coils, of a reactance connected across the terminals of the low tension coil, and a ground connection from approximately the neutral point of the reactance coil protecting the low tension circuit against excess of voltage from the high tension circuit.

ROBERT V. BINGAY.
